ELECTRONIC LOCKING CIRCUIT

Arthur E. Canfora, Brooklyn, N. Y., assignor to
 Radio Corporation of America, a corporation
 of Delaware

Application June 28, 1945, Serial No. 601,957

5 Claims. (Cl. 250—27)

1

This invention relates to locking circuits. More particularly, the invention relates to a device having the characteristics of an aperiodic trigger circuit such as is commonly used in code signal keying and electronic switching.

It is an object of my invention to provide a locking circuit which shall be more stable in operation than those heretofore used where it was necessary to obtain a substantially exact equation between the triggering potentials applied reciprocally to the input circuits of two discharge tubes.

It is another object of my invention to provide a dual triode locking circuit of the type which makes use of a gaseous glow tube for performing the function of interaction between the two triodes of the locking circuit.

A feature of my invention consists in the substitution of a neon lamp or the equivalent for a resistor in one of the cross-connections between the anode of one tube and the control grid of a second tube.

In the conventional locking circuit two discharge tubes are provided having interconnected control circuits such that the anode of each tube supplies triggering potential to the control grid of the other tube. Such a locking circuit must be designed, built and operated within close tolerances, particularly as to the values of the voltage divider elements which extend from the anode of each tube to the negative terminal of a biasing source. It is also necessary to select with great care the proper tapping point along these voltage dividers for supplying control potentials to each grid. Then again, the supply voltages must be maintained within a close range of the theoretically calculated value in order to avoid improper operation of the circuit.

When locking circuits are used in pulse counters of the binary type, it was sometimes found advantageous to employ neon lamps merely as an accessory to the conventional locking circuit for the purpose of indicating the number of counts registered. Such lamps did not, however, contribute in any way to the dependability of the locking circuit action.

According to my invention, a gaseous glow tube or neon lamp is introduced into the circuit for the purpose of contributing materially to the stabilizing of the locking circuit action, in addition to acting as an indicator. The glow tube is a gaseous diode.

My invention will now be described in more detail reference being made to the accompanying drawing the sole figure of which represents

2

diagrammatically a preferred circuit arrangement.

The drawing shows two triode discharge tubes 1 and 2. A source of operating potential 3 is shown having four sections E₁, E₂, E₃ and E₄ respectively. If desired the source 3 may have connected across its terminals a voltage divider from which taps may be taken off for supplying the necessary potentials of different values to different parts of the circuit. The cathode 4 in tube 1 is connected to the junction between sections E₂ and E₃ of the source 3. The anode 5 is connected through a resistor 6 to the most positive terminal of the source 3. The control grid 7 is connected through a resistor 8 to ground and to the junction between sections E₁ and E₂ of the source 3.

Triode tube 2 has its cathode 9 connected to the junction between sections E₃ and E₄ of the source 3. The anode 10 is connected to ground through the resistor 8. The connection between the anode 10 and the control grid 7 in tube 1 has a negligible resistance value. A voltage divider comprising three sections 11, 12 and 13 is connected between ground and the most negative terminal of the source 3. The junction between voltage divider sections 12 and 13 is connected to the control grid 14 in tube 2. The junction between voltage divider sections 11 and 12 is connected through a gaseous glow tube 15 to the anode 5 in tube 1.

An input circuit having terminals 16 is shown connected between the control grid 7 and ground. An output circuit 17 is shown having one terminal connected to the anode 5 and the other terminal grounded. Both the input and output circuits may be differently connected, however, in various ways, as will be understood by those skilled in the art. The choice of positions for taking off the output is largely determined by the wanted polarity of the signals.

The operation of the circuit will now be described. Assume that tube 1 has been rendered conductive by a positive pulse applied across the input terminals 16. The reduced anode potential in tube 1 due to a voltage drop across resistor 6 causes tube 15 to be extinguished. The bias potential applied to grid 14 in tube 2 is then determined by the voltage drop through the several sections 11, 12 and 13 of the voltage divider to which this grid 14 is connected. The values of the voltage divider sections are so determined that tube 2 will be biased to cut-off under these conditions.

It should be noticed that the potential of the

cathode 4 is maintained at a negative value with respect to ground. The anode potential in tube 1 can, therefore, be allowed to approach ground potential so as to render it impossible for the neon tube 15 to be ignited so long as tube 1 remains conductive. The resistance between the anode 5 and the junction between voltage divider sections 11 and 12 is, therefore, infinite.

Let it now be assumed that a negative signal pulse is applied across the input terminals 16, thereby biasing the grid 7 in tube 1 so far negative as to render tube 1 non-conductive. Then the anode potential in this tube is raised sufficiently high to cause the neon tube 15 to ignite. The junction between voltage divider sections 11 and 12 now receives a potential boost from the most positive terminal of source 3. In other words, a circuit is established from the most negative terminal of the source 3 through voltage divider sections 13 and 12, thence through the neon tube 15 and through resistor 6 to the most positive terminal of source 3. Under this condition the grid 14 in tube 2 is positively biased and causes this tube to be conductive. Current now flows from the cathode 9 through the tube, and through resistor 8 to ground. This biases the grid 7 negatively and produces a locking action such that tube 1 becomes non-conductive. By properly proportioning the resistor values it is possible to obtain a very considerable voltage swing on the grids 7 and 14, as between positive and negative values with respect to their cathodes. Thus the circuit is rendered less critical in respect to the values of the input potentials; and, furthermore, the stability of action is assured.

The interdependence of action of each tube upon the other involves a control voltage swing the range of which is extended by the use of the neon lamp 15. The lamp produces a self-switching action to open and close its circuit between the anode 5 and the junction between voltage divider sections 11 and 12. This junction point is thus flooded with high positive potential at one time, that is, during the conductive state of the neon tube 15; yet when this tube is extinguished the voltage divider is entirely isolated from the action of tube 1.

The stability of action of tube 1 depends also, to some extent, upon the substantially negligible resistance value of the connection between its grid 7 and the anode 10 in tube 2. Tube 1 is always biased to cut-off while tube 2 remains conductive, that is, until a sufficiently positive impulse is applied across the input terminals 16. It should be observed, however, that the potential of the anode 10 while tube 2 is conductive can be made considerably more negative than the cathode 4 in tube 1, due to the chosen values of the power supply sections E₂, S₃ and E₄.

My invention has utility in many of the commonly known circuit arrangements for telegraphy and for electronic counters, as well as in other applications.

I claim:

1. An electronic locking circuit comprising two vacuum discharge tubes each having a cathode, an anode and a control grid, a direct current source having suitable connections to different parts of said locking circuit whereby said tubes are activated one at a time, said connections including (1) a resistor in circuit between the anode of one tube and the most positive terminal of said source, (2) a connection of negligible impedance between the control grid of said one tube and the anode of the other tube, (3) a resistor in

circuit between said connection of negligible impedance and a grounded point intermediate the terminals of said source, (4) a voltage divider having three sections serially connected between ground and the most negative terminal of said source, the negative end of the middle section being connected to the control grid of said other tube, (5) a direct connection between the cathode of said one tube and an intermediate terminal of said source which is more negative than ground, (6) a direct connection between the cathode of said other tube and an intermediate terminal of said source which maintains this cathode more negative than the cathode of said one tube, and (7) a gaseous diode connected between the anode of said one tube and the positive end of the middle section of said voltage divider.

2. An electronic relay comprising two vacuum discharge devices each having a cathode, an anode and a control grid, a negligibly low resistance connection between the control grid of one device and the anode of the other device, a resistor connecting said connection to a point of reference potential such as ground, a direct current source having sections which supply a positive potential with respect to ground and three different potentials C₁, C₂ and C₃ which are progressively more and more negative with respect to ground, a resistive connection between the anode of said one device and the positive terminal of said source, a direct connection from the cathode of said one device to a source terminal which supplies potential C₁, a direct connection from the cathode of said other device to a source terminal which supplies potential C₂, a voltage divider having three sections connected between ground and a source terminal which supplies potential C₃, the middle one of said voltage divider sections being connected at its negative end to the control grid in said other device, and a gaseous diode connected between the anode of said one device and the positive end of the middle one of said voltage divider sections.

3. A trigger circuit comprising two vacuum discharge tubes each having a cathode, an anode and a control grid, a direct current source for maintaining the cathode of the first tube at a more positive potential than the cathode of the second tube, a resistive connection from the positive terminal of said source to the anode of the first tube, a direct connection between the control grid of the first tube and the anode of the second tube, a resistor connecting the grid of the first tube to a point of reference potential on said source which is more negative than the positive terminal of said source and more positive than the cathode of the first tube, means including a gaseous diode in circuit between the anode of the first tube and the control grid of the second tube for providing a trigger control of the second tube by the first tube, means for subjecting the control grid of the first tube to an externally derived signal control potential such as to render that tube conductive, and a voltage divider having three sections across which a potential drop is normally produced by said direct current source, one extremity of said voltage divider being maintained at a positive potential with respect to the cathode of the first tube, the other voltage divider extremity being maintained at a negative potential with respect to the cathode of the second tube, and the middle section of said voltage divider forming a connection between said gaseous diode and the control grid in said second tube.

4. In a circuit arrangement for producing an

aperiodic rectangular wave in response to the application of discrete control pulses from an external source of signals, the combination of two electron discharge devices each having an anode, a cathode and a control grid in a locking circuit so constructed and arranged that it has two positions of stability in either of which the locking circuit rests until tripped therefrom by control pulses of suitable variable absolute magnitude, said arrangement comprising means for applying said control pulses to the control grid of one device, potential sources coupled to the electrodes of said devices with the potential drop through the space path of the said one device in a more positive range than that through the space path of the other of said devices, output terminals for said locking devices, and a gaseous diode discharge tube in circuit between the anode of the one said device and the input circuit of the other said device to extend the range through which the magnitude of said control potentials may be varied above and below a critical range at which said tripping action takes place.

5. A locking circuit so constructed and arranged that it has two positions of stability in either of which positions the locking circuit rests until tripped therefrom by a control pulse of suitable polarity, said locking circuit comprising two electron discharge tubes each having an anode, a cathode and a control grid, a source of potentials of reversible polarity coupled to the control grid

and cathode of one tube, a direct current source having a plurality of intermediate taps in addition to its positive and negative terminals, said taps and terminals having individual connections to the anodes and cathodes of the tubes so that the voltage drop through one tube when it is conductive is in a more positive range than the voltage drop through the other tube when it is conductive, means including a gaseous diode tube in a lead between the anode of one tube and grid of the other tube for enabling a high anode potential in said one tube to drive the control grid in the other tube more positive, and a direct low impedance connection between the anode of said other tube and the control grid in said one tube whereby said one tube is rendered conductive when the other tube is biased to cut-off.
